CLAIM

The ornamental design for a storage container, as shown and described.

DESCRIPTION

FIG. 1 is a perspective view of a storage container showing my new design;
FIG. 2 is a right side elevational view thereof; the left side elevational view being a mirror image thereof;
FIG. 3 is a top plan view thereof;
FIG. 4 is a front elevational view thereof;
FIG. 5 is a bottom plan view thereof;
FIG. 6 is a rear elevational view thereof; and,
FIG. 7 is a perspective view of a second embodiment of FIG. 1 thereof.

The corresponding views of FIG. 7 embodiment are same as shown in FIGS. 2, 4, 5 and 6.

FIG. 1

FIG. 2

FIG. 3

FIG. 4

FIG. 5

FIG. 6
